UNITED STATES PATENT OFFICE.

MELVILLE CLARK, OF CHICAGO, ILLINOIS, ASSIGNOR TO MELVILLE CLARK PIANO COMPANY, OF CHICAGO, ILLINOIS, A CORPORATION OF ILLINOIS

PNEUMATIC ACTION FOR INTERIOR PIANO-PLAYERS.

1,169,126.

Specification of Letters Patent.

Patented Jan. 25, 1916.

Application filed June 24, 1914. Serial No. 847,008.

To all whom it may concern:

Be it known that I, MELVILLE CLARK, a citizen of the United States, residing at Chicago, in the county of Cook and State of Illinois, have invented new and useful Improvements in Pneumatic Actions for Interior Piano-Players, of which the following is a specification, reference being had to the accompanying drawings, forming a part 10 thereof.

The purpose of this invention is to provide an improved construction of pneumatic action for an interior piano player mechanism.

15 It consists in the elements and features of construction shown and described as indicated in the claims.

In the drawings: Figure 1 is a front elevation of a portion of a piano equipped with a 20 pneumatic action embodying this invention. Fig. 2 is a vertical fore-and-aft section at the line 2—2 on Fig. 1. Fig. 3 is a section at the line 3—3 on Fig. 2, showing a rear elevation of the pneumatic action. Fig. 4 is a section at the line 4—4 on Fig. 2. Fig. 5 is a detail view of movable supporting 25 connections employed for certain of the motor pneumatics. Fig. 6 is a section at the line 6—6 on Fig. 2, showing the interior of the primary pneumatic chamber and the arrangement of primary pneumatics therein. Fig. 7 is a section similar to Fig. 2 showing a modification for striking the manual keys.

Heretofore, it has been commonly customary in the construction of pneumatic actions for interior player mechanisms to mount the motor pneumatic supporting shelves upon the primary pneumatic chamber with a view to forming the ducts leading 30 from the valve chambers and controlled by the primary pneumatics in the substance of the walls of the primary pneumatic chamber and the motor pneumatic supporting shelves. This method of construction involves 35 expensive work in the formation of the ducts, gluing up the several layers of which the parts are necessarily formed in order to embody these ducts in the substance, and mounting the parts which are not glued 40 with great care as to the air-tight packing at the joints,—that is, between their contiguous surfaces. This mode of construction also makes the position of the motor pneumatics unchangeable and necessitates the 45 construction of a special action for each different 50 make of piano, by reason of the difference in the arrangement of spacing in different piano actions of the keys at their rear part, where the strikers of the pneumatic player action reach and act upon the piano keys or the striker or elements of the hammer action of the piano, which are similarly varied in their spacing in different 55 makes of pianos.

The present invention aims to avoid the difficulties and defects above pointed out by construction permitting the connection of the valve chambers of the primary action directly with the respective motor pneumatics by detachable flexible ducts, as is common 60 in connecting the tracker ducts with the primary pneumatics. In conjunction with this feature, the present invention contemplates a condensed arrangement of the primary pneumatics in the primary pneumatic chamber which is rendered possible without complexity by the adoption of the flexible tube connection from the primary pneumatic valve chambers to the motor pneumatics.

In the structure shown in the drawings, the primary pneumatic chamber, 1, which has an exhaust air trunk connection, 2, conveniently made at either end as shown, has mounted within it primary pneumatics, 3, 65 each supported upon a duct bar, 4, these duct bars being extended between, and rigidly connected to, top and bottom rails, 5 and 6, of the chamber, 1, and having nipples, 7, which provide for connection of the ducts of 70 said bars respectively by means of flexible tubes, 8, with the tracker ducts, extended through the upper rail, 5, and so serving as hollow dowel connections for the duct bars with the rail, and rendering of secondary 75 importance the glue joint which is preferably also formed between the upper ends of the bars with the rail. The lower ends of the duct bars are secured to the lower rail, 6, by screws, or in any other mechanically 80 convenient manner. The primary pneumatics, 3, of bellows form have their lateral folds protruding outward so as to obtain the largest air capacity within a given lateral dimension. The bars, 4, upon which 85 the pneumatics are mounted are not required to be wider than the stiff vibrating member of the pneumatic, and the lateral folds of the pneumatic, therefore, overhang or extend beyond the lateral edges of the bars. 90

Advantage is taken of this to reduce to the minimum the dimensions of the primary pneumatic chamber, 1, which is accomplished by making alternate primary pneumatics hinged at their upper ends, and the other alternate pneumatics hinged at their lower ends, the valves which they respectively carry being attached to their free or vibrating ends, and slightly staggering the 10 bars, 4, in the chamber so that the lateral folds of the primary pneumatics lap by each other without interference. By this means the height of the primary pneumatic chamber is reduced to scarcely more than the 15 length of one primary pneumatic, while the valves and valve chambers are still kept in two rows, as is necessary in order to accommodate them in the longitudinal space to which they must be restricted. The very 20 slight thickening or deepening fore-and-aft of the primary pneumatic chamber required for staggering the bars is of slight consequence in comparison with the reduction amounting to nearly one-half of the height 25 of the chamber by the expedient described.

The chambers, 10, for the valves, 11, operated by the primary pneumatics are all located in the same wall of the primary pneumatic chamber. This wall is for this 30 purpose formed in three layers, the chambers comprising slightly oblong holes through the middle layer, 12. The ports leading from the air chamber are made through the inner layer, 13. The valve chambers 35 are extended through the outer layer, and the ports, 10^a, leading to the outer air are made in strips, 14, 14, one for the primary pneumatics hinged at the upper end, and the other for those hinged at the lower end. 40 The middle layer, 12, has ducts, 15, leading from the valve chambers toward the lower edge of said middle layer, 12. These ducts laterally closed by the layers, 13, 13^a, extend to the lower edge of the middle layer, 12, 45 where they are all closed by a longitudinal bar, 16. This bar has ducts, 17, registering at the upper side of said bar with one out of three of the ducts formed in the middle layer leading from the valve chambers, and 50 said ducts, 17, lead out through the rear edge of said bar, 16, where they are furnished with nipples, 17^a, for connecting flexible ducts, 18, which lead to the motor pneumatics mounted on the upper shelf, as hereinafter described. The front layer, 13^a, has 55 apertures registering with the lower end portions of the ducts leading from the remaining valve chambers; and upon the forward side of the air chamber there is 60 mounted a strip, 20, having angle ducts, 21, which at the rear surface of the strip register with the apertures, 19, making communication with the ducts leading from said remaining valve chambers. The vertical 65 members of said angle ducts are provided

with nipples, 17^a, for receiving flexible tubes, 18, which connect with the motor pneumatics to be controlled by the primaries whose valve chambers are in the lower row.

Below the primary pneumatic chamber 70 there are mounted, preferably rigidly with said chamber, shelves in succession one below another, for supporting the motor pneumatics in three banks or levels, as is customary in order to allot to each motor 75 pneumatic sufficient space right and left for an operative width. The structure shown is specifically designed to operate by up-stroke upon the wippens of the hammer action of the piano, and the motor pneumatics are 80 therefore mounted upon the under side of the shelves, having their lower walls constituting the vibrating members for striking upward upon the wippens. As illustrated, therefore, there are three shelves or 85 supporting bars, 25 upon the under side of each of which there are mounted motor pneumatics, 26. Strikers, 27, are connected with the moving members of the pneumatics, 26, projecting upward from their connection, which is made in the usual manner, and extending through a guide bar, 28, for 90 positioning accurately their upper ends carrying the cushioned striker heads, 29, for acting upon the wippens. In order that the 95 motor pneumatics may be properly positioned to locate and space the strikers respectively, according to the spacing of the wippens in the particular piano action to which the player action is applied, said 100 motor pneumatics, or those of them corresponding to the portion of the hammer action in which there is usually variation in respect to the spacing of the wippens in pianos of different makes, are secured to 105 the shelves or supporting bars in a manner permitting them to be adjusted right and left thereon; and in order that such adjustment may be practicable, the flexible tubes connecting the motor pneumatics with the 110 ducts leading to the valve chambers controlled by the corresponding primary pneumatics must have considerable length, so that the change of distance from the end connected with the motor pneumatic to the 115 end connected with the nipple leading from the duct in the primary pneumatic chamber wall, caused by moving the motor pneumatic, shall be small relatively to the total length of said tube. The location of the 120 point of connection of the tube with the motor pneumatic at a suitable distance from its point of connection with the duct mentioned requires no special contrivance in respect to the motor pneumatics located on the 125 two lower shelves, because the distance downward from the duct nipples to the motor pneumatics on these lower shelves is adequate for the purpose; but with respect to the motor pneumatics mounted upon the 130

upper shelf, this vertical distance is not sufficient, and in the case of these pneumatics on the upper shelf the necessary distance is obtained by leading the duct out 5 through the rear side of the primary pneumatic chamber, and making the connection into the motor pneumatic at its rear end, so that the distance between the two end connections of the tube is nearly the entire 10 length of the motor pneumatic.

As a means for mounting and securing the motor pneumatics on the shelves or longitudinal supports so that they may be moved there-along to adjust them with respect to the spacing of the hammer action 15 or keys of the piano, there is mounted upon the edge of the shelf a metal channel strip, 30, made by folding a strip of thin metal longitudinally, the two plies being separated by a distance sufficient to admit without binding the vertical lip of a fitting, 32, which is secured upon the outer surface of the fixed member of the motor pneumatic at the portion thereof which protrudes beyond 20 the edge of the shelf. This fitting, 32, is hooked shaped in cross section, and the terminal hook lip, 34, is the portion which enters between the plies of the channel, 30, thereby hooking the motor pneumatic to the 25 shelf. The channel device is secured to the edge of the shelf by screws, 33, which extend through both plies near the fold and at a distance from the open edge of the channel at least as great as the distance to which 30 the hook lip, 34, of the fitting, 32, can intrude into the channel. By drawing these screws tightly, the channel is clamped together upon the intruded hook lip of the fitting, 32, and thereby the motor pneumatics 35 are held fixedly. By slackening the screws, 33, a little, the grip of the channel member upon the hook lip of the fitting, 32, is released, and the motor pneumatics can be moved along the channel to a new position 40 and again secured by tightening the screws. As many screws, 33, may be used in the length of the fitting as found necessary to attach it securely to the shelf and to clamp it to engage the hook lips of the 45 fittings, 32.

In order that the strikers may be provided with guidance near their hammer ends at all the different positions to which the motor pneumatics may be adjusted as above described, it is necessary that the guides for the strikers should be also adjustable right and left, or else the strikers will have to be disconnected whenever the motor pneumatics are adjusted to new position and the 50 strikers reinserted after the change is made through a new guide aperture corresponding to the changed position of the motor pneumatic. This latter method is feasible and may be employed with the structure 55 shown, but the disconnecting of the strikers

from the motor pneumatics is rendered unnecessary by the specific construction shown, which will now be described. Upon the rear edge of the upper shelf, there is mounted a channel bar, 40; opening rearward and facing this channel at a little distance from it 70 is a channel member made of a strip, 41, of quite thin metal folded longitudinally upon itself at the middle of its width, the two plies, 41^a, not being brought quite together 75 and each being folded outward at right angles at 41^b, at a little distance from the first fold, and then at right angles in the opposite direction at 41^c, into parallel position, forming a channel, 41^d, of the same 80 width as the channel of the member, 40, and facing the latter. Little bolts, 42, are set through the two plies, 41^a, to clamp them together and thereby close up or narrow the 85 channel, 41^d.

Between the two channel members and engaged in their channels there are positioned individual guide pieces, 45, preferably of some soft material, such as felt, for the 90 striker rods, each of said guide pieces having an aperture, 45^a, for the rod through which it may play freely. These guide pieces normally fit loosely enough in the two channel members so as to slide therein when the striker rods are moved along the channel 95 members in adjusting the motor pneumatics to their proper respective positions. When they are in proper position, the bolts, 42, being tightened, the lips of the channel, 41^d, are closed together and grip the guide 100 pieces, holding them securely against accidental displacement. The channel member, 40, is secured directly to the rear edge of the shelf by screws through its bottom web, and the channel member, 41, is secured to the 105 shelf by horizontal arms, 46, extended from the lower lip thereof at the ends; and it is further supported intermediate the ends by bracket pieces, 47, secured to the under side of the shelf and extending out under the 110 channel member, 41, having ends, 47^a, turned up to engage outside the lower right angle of said channel member. Positions may be chosen for these supports, 47, where they 115 will not interfere with any necessary adjustment of the motor pneumatics; but if in exceptional instances they should be found to interfere with such adjustments, they can be easily re-positioned on the under side of the shelf, being secured thereto by wood screws. 120

In Fig. 7, the distinguishing features of this invention are shown embodied in a pneumatic action having the strikers adapted to operate downward upon the keys, instead of upward upon the wippines of the 125 hammer action. The chief difference in construction consists in that the motor pneumatics are secured to the upper side of the shelves, instead of to the under side, in order to accommodate the stroke in the opposite 130

direction from that required in the construction shown in the previous figures, and that the principal portion of the length of the motor pneumatics projects forward from the vertical plane of the forward side of the primary pneumatic chamber instead of rearward of the plane, as in the preceding figures. Corresponding modifications are required in the position of the striker guide bar which is secured to the forward edge of the lower shelf instead of to the rear edge of the upper shelf. In this form, instead of the hooked fitting described for engaging the channel member on the edge of the shelf, the motor pneumatic requires only a simple angle fitting, 49, which is fastened by its horizontal lip to the under side of the motor pneumatic, its vertical lip engaging the channel of the member. In this form, another slight change due to the changed position and direction of stroke of the motor pneumatics consists in making the fixed member of the motor pneumatic extend beyond the hinge line of the vibrating member so as to have a surface exposed upward, through which the duct, 50, which leads into the interior of the pneumatic can open upward and receive the nipple, 51, for connecting the flexible tube leading from the proper valve chamber in the wall of the primary pneumatic chamber.

I claim:—

1. In a pneumatic action for piano players, a primary exhaust chamber and a row of primary pneumatics therein of bellows form, alternate pneumatics being offset slightly from each other in the direction of their expansion and contraction, whereby the bellows sides of consecutive pneumatics may overlap without interference.

2. In a pneumatic action for piano players, a primary exhaust chamber and a row of primary pneumatics therein of bellows form, and valves in rows at the moving ends of their vibrating members respectively, actuated thereby, alternate pneumatics being hinged at opposite ends, whereby the consecutive valves in each row may be spaced between centers as far as the space allotted to the width of two primary pneumatics.

3. In a pneumatic action for piano players, a primary exhaust chamber and a row of primary pneumatics therein of bellows form, valves at the moving ends of the vibrating members of said pneumatics respectively actuated thereby, alternate pneumatics being hinged at opposite ends and offset slightly from each other in the direction of their expansion and contraction.

4. In a pneumatic action for piano players, a primary pneumatic chamber and a horizontal row of primary pneumatics therein of bellows form, comprising pneumatics hinged at the upper end alternating with pneumatics hinged at the lower ends, those

hinged at opposite ends being also slightly offset from each other in the direction of their expansion and contraction; valves carried by the moving ends of the vibrating members of said pneumatics respectively, 70 one wall of the primary pneumatic chamber having valve chambers for said valves in two horizontal rows; ducts leading from said valve chambers in said wall toward the lower edge of the chamber, and thence out to an outer surface of the same, and nipples terminating said ducts for connection of flexible tubes leading to motor pneumatics to be controlled by the primary pneumatics, respectively. 80

5. In a pneumatic action for piano players, motor pneumatics and a fixed support for the same along which transversely to their lengths the motor pneumatics are movably distributed; strikers connected to the 85 vibrating members of the motor pneumatics respectively; guide pieces for the strikers respectively; a member in which the guide pieces are slidably mounted, said member being adapted and provided with associated 90 means for clamping the guide pieces releasably to permit them to be moved to new positions along said member.

6. In a pneumatic action for piano players, motor pneumatics and a fixed support 95 for the same along which transversely to their lengths the motor pneumatics are movably distributed; strikers connected to the vibrating members of the motor pneumatics respectively; guide pieces for the strikers 100 respectively; a support for said guide pieces comprising two channel bars having their channels facing each other for receiving the opposite ends of said guide pieces, one of said channel bars being compressible to diminish the width of the channel-opening for gripping the guide pieces between the marginal lips thereof. 105

7. In a pneumatic action for piano players, motor pneumatics and a fixed support 110 for the same along which transversely to their length the motor pneumatics are movably distributed; means for securing the motor pneumatics to the support, comprising a channel member mounted on the support 115 which is compressible to diminish the width of the channel, and fittings secured to the motor pneumatics respectively having lips adapted to enter said channels when the motor pneumatics are lodged on the support, 120 and means for releasably compressing the channel member to grip and release said lips.

8. In a pneumatic action for piano players, motor pneumatics and a fixed support 125 for the same along which transversely to their length the motor pneumatics are movably distributed; means for securing the motor pneumatics to the support, comprising a channel member mounted on the support 130 which is compressible to diminish the width

of the channel, and fittings secured to the motor pneumatics respectively, having lips adapted to enter said channels when the motor pneumatics are lodged on the support; and screws which secure the channel member to the support taking through both lips of said channel member into the support, whereby said screws secure said channel member to the support and serve to releas-

ably compress it to grip and release said lips 10 of the fittings.

In testimony whereof, I have hereunto set my hand at Chicago, Illinois, this 22d day of June, 1914.

MELVILLE CLARK.
